(57) **CLAIM**

The ornamental design for a dictation device, as shown and described.

DESCRIPTION

FIG. 1 is a front perspective view of a dictation device;

FIG. 2 is a front elevational view thereof;

FIG. 3 is a left side elevational view thereof;

FIG. 4 is a right side elevational view thereof;

FIG. 5 is a back elevational view thereof;

FIG. 6 is a top plan view thereof; and,

FIG. 7 is a bottom plan view thereof.

The broken lines in FIG. 7 are included for the purpose of illustrating a portion of the bottom that forms no part of the claimed design.

1 Claim, 4 Drawing Sheets

FIG. 1

FIG. 3

FIG. 2

FIG. 4

FIG. 5

FIG. 6

FIG. 7
